UNITED STATES PATENT OFFICE.

CHARLES E. YARIAN, OF GALION, OHIO.

TRAVERSING HOIST.

1,290,469.

Specification of Letters Patent.

Patented Jan. 7, 1919.

Application filed January 12, 1917, Serial No. 142,077. Renewed November 21, 1918. Serial No. 263,636.

To all whom it may concern:

Be it known that I, CHARLES E. YARIAN, a citizen of the United States, residing at Galion, in the county of Crawford and State 5 of Ohio, have invented certain new and useful Improvements in Traversing Hoists; and I do hereby declare the following to be a full, clear, and exact description of the invention, such as will enable others skilled in 10 the art to which it appertains to make and use the same.

This invention relates to traversing hoists and more particularly to that class of hoists designed to be used in handling coal, sand, 15 gravel, crushed rock and materials of similar description.

It has been found in practice that dealers in the above mentioned materials, who receive these products in carload lots, suffer 20 serious inconvenience in unloading and storing the same, owing to railroad regulations relative to the location of the storage bins of the dealer with respect to the company's tracks. As switches and sidings are only obtainable at considerable cost, and as this 25 cost is in proportion to the length of the siding, a siding of minimum length is greatly to be desired.

With these facts in mind, it is the object 30 of this invention to provide means for unloading material such as coal, crushed rock, sand, gravel, etc., from the car in which it is delivered to the dealer, conveying said material to its proper storage bin, said means 35 being adapted to receive the various materials at the same point on the same siding, and transfer them to their respective bins, which may be placed at any convenient location.

With this and other objects in view that 40 may more fully hereinafter appear, the invention contemplates the provision of a plurality of storage bins which are preferably located in a line at right angles to the tracks 45 of the siding, but through proper arrangement of the parts hereinafter described, the bins may be placed in any convenient location. The invention further comprises a traversing hoist provided with a novel cable 50 clamping device by which the conveyer bucket and its contents may be raised to any desired height prior to its journey to the bin, and retained, if desired, at this height

throughout its course, being automatically dropped at its bin by a trip located above 55 said bin on the overhead track.

One embodiment of my invention is hereinafter fully described and illustrated in the accompanying drawings, and more particularly pointed out in the appended claims, it 60 being fully understood that such changes in size and proportion of parts and in minor details of construction may be made as clearly fall within the scope of the appended claims without departing from the spirit or 65 sacrificing any of the advantages of the invention.

In the accompanying drawings:

Figure 1 is a side elevation of the overhead track with the traveling carriage 70 mounted therein, and the conveyer bucket suspended from said carriage.

Fig. 2 is a detail view, partly in section, showing the construction of the cable clamping device.

Fig. 3 is a sectional view taken on the line 5—5 of Fig. 2.

Fig. 4 is a fragmental sectional view of the overhead track, showing the manner of mounting the trips and means for actuating 80 the same.

Fig. 5 is a sectional view taken on the line 7—7 of Fig. 2.

Like reference numerals are used to designate like parts throughout.

Referring more particularly to the accompanying drawings and the embodiment of my invention disclosed therein, 40 designates an overhead track of any suitable material supported by any preferred means, such as upright members 41, and a plurality of overhead hangers 42, said track being provided with a plurality of longitudinal grooves 43 on its upper face designed to receive the rollers or wheels of the 90 traveling carriage, as will be hereinafter described.

The overhead track is carried above the various bins designed to receive the materials being unloaded and is provided above 100 each bin, with a spring actuated trip 44 mounted upon the underside of the track by means of suitable yokes or bearings 45, which are adapted to receive a pintle 46 upon which the trips are rotatably mounted. At the points on the track where it is

desired to mount said trips, the track is recessed as at 47, said recess having a cylindrical duct 48 communicating with the upper face of the track.

5 The trips 44 are provided on their upper faces 49 with a resilient member 51 secured to said trips by screws 50, said screws being provided with eyes 50^a designed to receive the rods 52, said rods extending upward through the ducts 48 and extending slightly above the upper face of the track, and having at their upper ends an eye 53 designed to receive a cable 54. The resilient members 51 are designed to engage 10 the upper faces 55 of the recesses 47 to return the trips 44 to their outward position.

15 The traveling carriage, designed to ride upon the overhead track 40, comprises a substantial frame 60 provided with a plurality 20 of wheels or rollers 56 suitably journaled on pintles 57, a separate and distinct pintle being provided for each roller, as clearly seen in Fig. 5. The purpose of this mounting of the wheels is to provide for the passage of 25 the overhead hangers 42, and the cable 54 between the rollers positioned on opposite sides of the frame, when the carriage is mounted on the track as shown in Fig. 5. The hangers 42 may be provided with suitable 30 apertures 58 to receive the cable 54.

35 Suspended from the carriage frame 60 by vertical members 59 is a frame 61 carrying a plurality of pulleys 62 and 63, said pulleys being rotatably mounted on suitable pintles 64 carried by said frame.

40 Suspended from the frame 61 by a plurality of cleats of equal length 65, is a frame 66. The cleats 65 are pivotally mounted to the frames 61 and 66 by suitable pintles 68, thereby allowing the frame 66 longitudinal motion with respect to the frame 61, and at the same time retaining the frames in a position parallel to each other.

45 Pivotal mounted on the frames 66 and 61 is a cable clamping device, best seen in Figs. 2 and 3. The frame 61 terminates at one end in enlarged portions 69 between which is rigidly positioned a gripping block 70, said block being provided with a plurality of teeth or corrugations 71. Pivotal 50 mounted between the opposite sides of the frame 66 upon pintles 72 is a pivotal jaw 74 having a corrugated face 74^a to coöperate with the corrugated face 71 of the gripping block 70, to clamp a cable passed between said faces, as hereinafter described. This 55 construction is clearly shown in Fig. 3, where is disclosed a plurality of legs 73 carried by the jaw 74 and by which said jaw is attached 60 to the frame 66. As shown in Fig. 3, the jaw extends upward between the opposite sides of the frame 61 and is rotatably connected to frame 61 by a pintle 75, said pintle carrying a suitable pulley 76.

65 The pulley 63 of the frame 61 is provided on its outer periphery with a plurality of teeth 77, designed to engage a bar 77^a carried by the legs 73 of the jaw 74, when said jaw is rotated on pintle 75 by a longitudinal movement of the frame 66 as will be herein- 70 after fully described.

75 Suspended from the traveling carriage by a suitable cable 78 fastened to a bar 79, carried between the opposite sides of the frame 61, is a frame 80 from which is suspended a suitable conveyer bucket 87. The frame is shown provided with a plurality of pulleys 81 and 81^a suitably journaled on pintles 82 carried by said frame. The cable 78 is led downward from the bar 79 through the 80 pulley 81 upward and around pulley 62, thence downward and through pulley 81^a, thence upward and around toothed pulley 63, thence over the pulley 76 of the jaw 74 between the legs 73 thereof and the faces 85 74^a and 71 of the jaw and the gripping block, respectively, and thence by means of a swiveled pulley 83 to the drum of a hoist.

85 The operation of the device is as follows:

90 The bucket having been lowered and filled in the usual manner is then raised by applying power to the cable 78 to any desired height, and when such height has been attained, power is applied to the cable 84, thereby communicating longitudinal movement to the frame 66 in the direction in which the force is applied, causing the pivoted jaw 74 to rotate on its pintle and come into clamping engagement with the cable 78 95 passing between the corrugated faces 74^a and 100 71, at the same time bringing the bar 77^a into mesh with the teeth of the pulley 63, thereby effectively locking the same. Power is then removed from the cable 78 and through the force applied to the carriage by 105 means of the cable 84, the traveling carriage proceeds along the overhead track.

110 The pivoted jaw 74 is provided with an extended portion which terminates in close proximity to the underside of the overhead track, and is so positioned as to engage the trips 44 mounted thereon. It is evident 115 from the foregoing description taken in connection with the accompanying drawings that the trips are so mounted as to permit of the free passage of the carriage in one direction, but will offer obstruction to its passage in the opposite direction. Having this in mind, the carriage is pulled freely 120 along the track until the desired storage bin is reached, above which is positioned a trip. The carriage is pulled past the trip, said trip being forced into its recess by the end of the jaw 74, and said trip being forced outward 125 into its operative position by the resilient member 51. The carriage is then pulled back so as to bring the extended portion of the jaw into engagement with the vertical

face of the trip, thereby causing the jaw to be opened, the cable to be released, and the bar 77^a to be drawn from engagement with the teeth 77 of the pulley 63, allowing the bucket to be lowered.

When the contents of the bucket have been discharged, the bucket is raised to any desired height and a slight pull given to the cable 84 to clamp the cable 78 between the jaw 74 and the gripping block 70, and to bring the bar 77^a into engagement with the teeth of the pulley 63, thus effectively locking the bucket at the desired height. The cable 54 is then pulled to draw the trips into their respective recesses, thereby allowing the carriage free passage along the track. When the carriage has passed the last trip before the one located above the loading pit, the cable 54 is released, allowing the trips to resume their operative position. The jaw 74 coming into contact with the trip, thus placed in operative position, is opened and the cable and pulley released, as before described, and the bucket lowered for reloading.

Having thus fully described my invention what I claim is:—

1. The combination with a track, of a carriage to ride thereon, a bucket suspended from the carriage, means to raise and lower the bucket with respect to the carriage, means carried by the carriage to retain the bucket at any desired height, and coöperative means between the carriage and the track to release the bucket at a plurality of predetermined points.

2. The combination with a track, of a carriage, comprising a plurality of relatively movable frames, a cable, a bucket suspended from one of the frames thereby, and means to retain the bucket at any desired height, said means being operable through the movement of one of the frames.

3. The combination with a track, of a carriage to ride thereon, a cable, a movable frame carried by the carriage, a gripping block, means carried by the carriage and the movable frame to clamp the cable against the gripping block, and means to actuate the cable clamping means.

4. The combination with a track, of a carriage to ride thereon, a jaw pivotally mounted on the carriage, a gripping block, a frame movable with respect to the carriage, and means whereby the movement of said frame will move the jaw into and out of engagement with the block.

5. In a device of the class described, a conveyer carriage comprising a plurality of frames, one of said frames suspended below the other, said suspended frame being capable of longitudinal movement with respect to the other, a gripping block carried by one of said frames and a jaw pivotally attached to

both of the frames to coöperate with the gripping block to form clamping engagement therewith.

6. In a device of the class described, the combination with a conveyer carriage, of a cable clamping device comprising a jaw pivotally attached to the carriage at a plurality of points, a gripping block to coöperate with the jaw, means to provide for the longitudinal movement of one section of the carriage with respect to another section thereof, to bring the jaw into clamping engagement with the gripping block.

7. The combination with a track, of a carriage to ride thereon, a cable, a jaw carried by the carriage, a gripping block to coöperate therewith, a frame movable with respect to the carriage, means whereby the movement of said frame will bring the jaw into locking engagement with the cable, and means on the track to release the jaw from said locked position.

8. The combination with a track, of a carriage to ride thereon, said carriage comprising a plurality of frames, one of said frames having longitudinal movement with respect to the other, a pulley carried by one frame, means to engage the pulley to prevent its rotation, and means whereby the movement of one frame with respect to the other will move said means into and out of engagement with the pulley.

9. The combination with a carriage comprising a plurality of relatively movable frames, of a cable clamping mechanism, a plurality of pulleys, a cable to engage the pulleys, a pulley locking mechanism, and means to simultaneously operate both mechanisms by the movement of one of the frames, with respect to the other.

10. The combination with a carriage comprising a plurality of relatively movable frames, of a plurality of pulleys, a cable to engage the pulleys, means pivotally connected to the two frames to engage the cable, means carried by said cable engaging means to simultaneously engage a pulley, and means to move one frame longitudinally with respect to the other to thereby bring said pivotal means simultaneously into and out of engagement with the pulley and the cable.

11. The combination with a carriage having a plurality of relatively movable frames and a cable clamping device pivotally connected to each, of a cable, and a guide pulley carried by the clamping device to direct the cable through the device in an operative position.

12. The combination with a track, of a carriage to ride thereon, a cable, a plurality of pulleys, means to simultaneously lock the cable and a pulley, and means to release said locking means at a plurality of predetermined points.

13. The combination with a track, of a carriage to ride thereon, a cable, a plurality of pulleys, a bucket suspended from the carriage by the cable, a frame movable with respect to the carriage and carried thereby, means operated through the movable frame to retain the bucket at a predetermined

height, and means on the track to release the bucket at a plurality of predetermined points.

10

In testimony whereof, I affix my signature.

CHARLES E. YARIAN.
